UNITED STATES PATENT OFFICE.

EDWIN A. SCHOLFIELD, OF WESTERLY, RHODE ISLAND.

LOOM.

Specification of Letters Patent No. 18,061, dated August 25, 1857.

To all whom it may concern:

Be it known that I, EDWIN A. SCHOLFIELD, of Westerly, Washington county, and State of Rhode Island, have invented a new and 5 useful Improvement in Looms for Weaving Either Plain or Variety Goods, and that the following is a full, clear, and exact description of my said improvement, reference being had to the accompanying drawings, 10 making part of this specification.

The principle of my invention consists in drawing the cam wheel which acts on the harness, not by a uniform motion, but, by an intermittent and variable motion; its 15 periods of intermission and change coinciding with those of the springing or changing of the harness and is as follows, viz;

A Figure 1st is a cam wheel acting so as 20 to raise the lever L by the action of the cams 1, 2, 3, &c., on the shoe or step d of the levers which are hung on the bolt or fulcrum b. These levers are made of iron and are enlarged or weighted at the extremity C at 25 which place they are to be connected with the harness and act by forcing the harness upward while the heft of the levers and weights c bring the harness down when left free from the actions of the cams.

Fig. 2 is a face view of the cam wheel 30 which consists of any number of circular plates a according to the number of harnesses to be used, (that in the drawing represents eight) with cams or tappets 1, 2, 3, &c. on their surfaces: these act on an equal 35 number of levers L Fig. 1 to raise the harness, the weight of the levers and their enlargements C are sufficient to bring the harness down again after the cam ceases to act thereon.

B is a disk wheel having slots from the 40 circumference toward the center in such manner that two stud pins e Fig. 3 may act therein as the driving disk wheel f with its two opposite studs revolves and carries the 45 disk wheel B along with it. The slots are at just sufficient distance from each other at the surface that one of the stud pins e shall enter one of the slots while the other stud is leaving its slot, and they must be of sufficient length downward to suffer the disk 50 wheel f to revolve freely without carrying the studs e hard on the bottom. From these premises it is apparent that by the revolution of the disk wheel f with its studs e the 55 slotted disk wheel B is put in motion as one gear wheel would communicate motion to

another, but that the action of the wheel B is by this communication intermittent and variable. Thus while in action and in the position as shown in the drawing Fig. 3 the 60 action of the stud e of the disk f is the greatest possible on the disk B, that is the motion of B is to that of f as e h the radius f to e g the radius B. But when both the studs e are brought to coincide with the circumference of the disk B or while one is entering 65 and the other leaving the slots the motion of B is the least possible or in a theoretic state of rest. The result of which is that the harness may be raised and brought down suddenly by a concentrated action at the time 70 of change and suffering them to be extended during some definite and suitable time still allowing a free and easy shape to the cams which act thereon. Without this intermittent and concentrated action of the studs e in the disk B the cams 1 2 3 &c. on the cam wheel A Fig. 1 would require to be so shaped 75 as to move the levers and harnesses with a suitable rapidity and to delay their action thereon through suitable intervals of time to allow a proper action of the loom. And when an intense concentration of action is exerted by any cam by giving it such form 80 as to act intensely through a small amount of space, its action is laborious and unsteady 85 and jarring, injurious alike to the machinery and the product of its action, but whenever in the concentration of action if it can be effected by dividing this concentration between two or more parts which act as motors 90 in producing this concentration, the results are attained with an ease and smoothness otherwise impracticable. And in fact it is 95 found by the use of this improvement that a loom operates much easier than without, and can be run in either direction backward or forward with equal facility.

The cam wheel may be from 8 to 12 inches in diameter, and the disk wheel B may be 100 of about the same size the circular plates a of the cam wheel Fig. 2 should be about $\frac{3}{4}$ inch thick, and the cams or tappets 1, 2, 3, &c. should be about $\frac{1}{2}$ inch thick and should be about 2 inches high from the face of the 105 circular plates, and they may be in shape nearly as shown in Fig. 1, and the shoe d on the lever may be nearly as there shown. Two inches rise over the cam wheel would give about 4 or $4\frac{1}{2}$ inches at the center C 110 of the swell; at which point the connection should be made for the action of the harness.

- Instead of cams to act on the shoe of the levers, rollers *r* may perform that office as shown at Fig. 4. These rollers may be supported on journals in their circular plates 5 as shown at Fig. 5, the plates being about $\frac{3}{16}$ inch thick and being about $\frac{1}{2}$ inch distant to allow a roller $\frac{1}{2}$ inch thick, or cams may be used as at Figs. 1 and 2 while rollers are attached to the levers in place of the shoes 10 *d*. Rollers may also be fitted on the studs *e* to act in the slots of the disk wheel *B* having these slots enlarged to the capacity of such rollers and with these changes, the motions will be effected easier than otherwise. 15 This improvement is applicable to looms for weaving plain or variety goods and dispenses with all the upper fixtures for raising the harness usually employed especially in complicated work. 20 The cams or rollers of the cam wheel may be placed in any order of succession desired, according to the kind of goods to be woven; and this order may be easily changed by taking the circular plates apart and rearranging them or by having others to put in 25 their places. Some of the advantages of this mode of driving the cam wheel for operating the harness by means of the star gears to give a variable motion thereto, are; that the 30 cam wheel may be much smaller, while carrying the same number of cams or changes, than when driven with a uniform motion, or if of the same size it may carry a greater number of cams or changes, and

consequently a greater variety of patterns 35 may be woven with this application than without. For if on a small cam wheel a large number of cams is attached, these in order to give the proper action to the harness must necessarily be set very steep, so 40 as to act abrupt, and harshly thereon, but by the intermittent and variable action, the cam may be more open and free; its action being timed by the accelerated and retarded motion given by the star gears. 45

I am aware that the star gears under a modified form have been used for changing the position of the shuttle box, and also the pattern chain which governs the order of succession of the harness (as in the patents 50 of Samuel Eccles of March 1850, and of Samuel and James Eccles of August 1852); but these are for totally different objects from that contemplated in this. Therefore I do not claim the construction, or use of 55 star gears, for any purpose except to drive a cam wheel to spring the harness in weaving.

What I claim as my invention and for which I solicit Letters Patent is—

The driving a revolving cam or tappet 60 wheel, which acts to spring the harness or produce a shed in weaving, by an intermittent or variable motion, by the use of star gears, substantially as above described.

EDWIN A. SCHOLFIELD.
